METHOD AND APPARATUS FOR AIR SEPARATION OF DIATOMACEOUS EARTH MILLING

McKinley Stockton, Los Angeles, Calif., assignor to The Dicalite Company, Los Angeles, Calif., a corporation of Delaware

Application July 23, 1932, Serial No. 624,306

7 Claims. (Cl. 209—138)

- This invention relates to machinery for classifying diatomaceous earth and the like, and particularly pertains to an air classifier for such purpose, and the method of using the same.
- 5 Beds of diatomaceous earth suitable for commercial operations usually contain bands of hard dark colored silica termed flint rock, nodules of more or less hardened concretions resembling shale, and a small percentage of sand. In mining or quarrying diatomaceous earth every effort is made to eliminate these impurities, but it has heretofore been found to be impossible to completely separate the impurities from the desirable earth. It is highly desirable in the milling of 10 diatomaceous earth to remove these objectionable particles, as they are a great source of trouble when present in any product, whether used as a filtration medium, as a filler, or for other purposes.
- 15 It is the principal object of the present invention to provide a method of operation and means whereby the undesirable particles of rock, nodules of hardened concretions and particles of sand may be readily separated from the desired finished product, and may be effectually rejected so that they will not again commingle with the product and so that in the particular operation with diatomaceous earth a product of uniform character 20 may be obtained.
- 25 The present invention contemplates the provision of suitable diatomaceous earth milling machinery delivering its comminuted material to air separation means within which the desired and rejected particles will be suspended in a fluid 30 medium and will gravitate in such manner as to insure that objectionable particles will be completely rejected from the material passing through the apparatus.
- 35 The invention is illustrated by way of example 40 in the accompanying drawing, in which:—
- The figure is a view in vertical section showing a diagram of the apparatus with which the present invention is concerned.
- 45 Referring more particularly to the drawing, 10 indicates a conduit through which comminuted diatomaceous earth and associated particles are delivered to a vertical pipe 11, the lower end of which pipe is suitably connected with a centrifugal blower 13. The upper end of the vertical pipe 11 communicates directly with an air classifier 14 which has a frusto-conical section 15 terminating at its upper enlarged end in a cylindrical shell 16. The upper end of the shell 16 is closed by a 50 conical top section 17 through the apex of which a main eduction pipe 18 extends. The longitudi-
- dinal axis of the eduction pipe 18 is coincident with the vertical axis of the classifier 14 and the longitudinal center line of the inlet pipe 11.
- 55 Mounted within the main shell of the classifier and spaced therefrom is a separating cone 19. The upper end of this separating cone member comprises a cylindrical portion 20 entirely opened at its upper edge. The cylindrical wall is concentric with the outer cylindrical shell 16 and is spaced therefrom to form an annular vertical 10 passageway 21 between the classifying member 19 and the shell. The lower end of the eduction pipe 18 projects a suitable distance into the mouth of the cylindrical portion 20 of the classifying member and since it is arranged in concentric 15 relation to the cylindrical portion 20, an annular passageway 22 will be provided as a continuation of the passageway 21, so that materials in fluid suspension will be carried upwardly within the shell along the annular passageway 21 and into 20 the mouth of the classifying member 19 through the annular passageway 22.
- 25 This arrangement ensures that the material which is being carried through the apparatus will be given a complete reversal of direction of travel, 30 since it will make a turn of 180° as it passes over the edge of the mouth of the cylindrical portion 20, and then passes upwardly through the eduction pipe 18. The areas of the annular passageways 21 and 22 and the area of the passageway 30 through the eduction pipe 18 are so proportioned as to insure that heavy particles such as flint, shale and sand will continue to travel under the force of its gravity and the additional force of 35 gravity toward the bottom of the classifying element 19, and will not make the turn into the eduction pipe 18. This heavy material then flows downwardly into the restricted inverted conical throat 23 of the classifying unit 19 and into a drawoff pipe 24 which extends through the side 40 wall of the shell and communicates with the upper end of a tailings separator 25.
- 45 This separator includes a conical bonnet 26, the apex of which directly connects with the draw-off pipe 24, and the base of which conical member 45 is provided with a cylindrical shell 27. Shell 27 telescopes into a cylindrical member 28 which terminates in an inverted conical portion 29, the apex of which is opened as indicated at 50 to permit the finally rejected material to fall from the 55 separator.
- A suction pipe 31 extends into the upper cylindrical portion 27 of the second separator and has a down-turned portion 32 which projects into the mouth of the lower cone 29 and is disposed 55

eccentrically thereto. The pipe 31 connects with the pipe 10 and a flow of air therethrough is caused by the blower 13 as it draws the feed supply through the pipe 10 and forces it upwardly through the pipe 11.

The cylindrical portions 27 and 28 of the two sections of the tailings separator telescope one within the other and may be adjustably set by suitable set screws 33, thus varying the extent of contact of the heavy grains with the air stream drawn through discharge opening 38 and permitting all the light material to be removed from the heavy grains and returned to the main classifier 14 without returning any of the heavy grains.

In order to regulate the velocity of air flow through various parts of the apparatus a suitable damper 35 may be placed in the draw-off pipe 24, and a damper 36 may be placed in the suction pipe 31. This provides additional adjustment and control of the air velocity through the tailings separator for the proper suspension of the materials therein. It is also desirable to provide a telescoping joint for the eduction pipe 18 at the upper end of the main classifier so that it may be adjustably telescoped into the mouth of the classifying unit 19, making it possible to accurately select a desired grade of product or to accommodate products having different characteristics. Attention is directed to the fact that while this apparatus has been described as operating on fluid pressure applied to the induction end of the main classifier it might prove highly desirable in some instances to reverse the arrangement and cause the air to travel through the apparatus under action of suction applied to the eduction pipe 18. This, of course, could be done without departing from the spirit of the present invention.

The air drawn into the apparatus may be first passed through a suitable air heating furnace 40 and may thereafter be drawn along the pipe 10 to receive the material to be treated from a suitable hopper 41 having a valve seal 42. It has been found that in a suspending medium of heated air separation of the particles of earth is more readily affected than when cold air is used and that the tendency of the earth to agglomerate or ball is avoided. The temperature of the air may be varied, but it has been found that a maximum temperature of 600° F. is quite suitable for present purposes.

In operation of the present invention, a material to be classified, specifically diatomaceous earth is delivered to the induction pipe 10 in a desired state of comminution, produced by any suitable milling equipment. It is usually the case that the finely divided material is mixed with particles of flint rock, shale and sand and in order to produce a final product worthy of use as a filtration medium, a filler, or for any other commercial purpose it is necessary to eliminate these extraneous particles.

The material delivered through the induction pipe 10 is delivered into the vertical pipe 11 through suction action of a blower 13. The flow of air from which blower creates an upwardly flowing stream of air within the pipe 11 and causes the particles of the material delivered through pipe 10 to be suspended therein and elevated thereby. During this elevation, turbulence in the blower tends to disperse the agglomerate material and to separate particles which vary in gravity. The air pressure developed by the blower may be approximately determined, but it has

been found that a blower having a capacity of 12,000 cu. ft. of air per minute is adequate for present purposes in the treatment of diatomaceous earth.

As the air travels upwardly at high velocity it projects the particles of greater density against the cover member 14, and as the air makes a turn of 180° as it passes over the lip of the cylindrical member 20, the heavy materials move downwardly at a greater rate of speed than the lighter materials, since their speed of travel is accelerated by the action of gravity. The air is then given a reverse turn of 180° so that it follows a sinuous path of travel in reverse directions, first over the lip of the cylindrical member 20 and then around the edge of the eduction pipe 18 and into the vertical passageway therethrough. The lighter solid particles are carried upwardly through the pipe 18 since the gravity effect is insufficient to overcome the velocity of the air stream in which they are suspended. These lighter particles are in the present instance the desired product.

The heavier tailings fall of their own weight into the inverted cone 23 of the classifying unit 19, this movement being accelerated by a flow of air downwardly through the relatively restricted draw-off pipe 24. This effect may be controlled and varied by the operation of dampers 35 and 36. Further controls are provided by the adjustable relationship of the eduction pipe 18 to the cylindrical portion 20 of the separator 19, by the relative adjustability of the two sections of the tailings separator. In practice it has been found that by proper adjustment of the various elements, substantially all of the undesired extraneous matter may be rejected from the supply of the product being fed into the apparatus, and that a substantially uniform product may be drawn off through the eduction pipe 18.

It is to be further pointed out that variations in temperature of the product being treated and the velocity with which it is carried through the apparatus may act to produce different final products, and such variations are here contemplated if desired.

It will thus be seen that by the use of the apparatus here disclosed in the manner set forth, it is possible to rapidly and continuously classify materials either to recover the lighter fraction of material or the heavier particles if desired.

While I have shown the preferred form of my invention and a method of operation, it is to be understood that various changes might be made in the combination, construction and arrangement of the parts, and that variation might be made in the steps of the method without departing from the spirit of the invention as claimed.

Having thus described my invention, what I claim and desire to secure by Letters Patent is:

1. Apparatus for the separation of heavy granular particles from comminuted diatomaceous earth, comprising: a primary separator adapted to effect an initial separation of said granules from a column of air carrying said earth in suspension and having an interior chamber adapted to collect said granules; means for introducing said air and said earth into said primary separator; a blower arranged to maintain said air column in motion; a secondary separator comprising a shell having an outlet for said granules from the lower part thereof; a channel arranged to permit said granules to flow by gravity from said interior chamber of said primary separator.

arator into the upper part of said secondary separator, and means for causing a secondary air stream to enter said secondary separator through said granule outlet and in counterflow to said granules and for causing said secondary air stream to leave said secondary separator at a level intermediate its ends and to return to the intake end of said primary separator.

2. Apparatus substantially as and for the purpose set forth in claim 1, in which said last means comprises a channel affording communication between the interior of said secondary separator and the suction of said blower.

3. Apparatus substantially as and for the purpose set forth in claim 1, in which said secondary separator is a cylindrical vessel having a conical bottom, said outlet being formed by truncating said cone.

4. Apparatus substantially as and for the purpose set forth in claim 1, in which the shell of said secondary separator consists of mating cylindrical portions arranged to telescope and thus to adjustably vary the vertical distance between said outlet for granules and the point of admission of said granules.

5. Apparatus substantially as and for the pur-

pose set forth in claim 1, including valve means in said channel for the flow of granules.

6. Apparatus substantially as and for the purpose set forth in claim 1, in which last said means comprises a channel affording communication between the interior of said secondary separator and the suction of said blower, and including valve means in said communication channel.

7. Apparatus for air classification of diatomaceous earth comprising: a substantially closed and vertically arranged outer shell having a conical bottom; an inner shell having a conical bottom and an open top, said inner shell being spaced from and concentric with said outer shell; a conduit connected to the lower end of said outer shell; means for feeding material to said conduit; a blower within said conduit to comminute the material entering said outer shell and arranged to maintain a slight superatmospheric pressure within said shells; a channel arranged to pass granular solids and air from the lower end of said inner shell to a point exterior said outer shell, and a vent pipe passing through the upper head of said outer shell and extending into the open upper end of said inner shell. 25
